GRILLE STRUCTURE

Vernon Dell Castle, Waterloo, Iowa, assignor to
 Titus Manufacturing Corporation, Waterloo,
 Iowa, a corporation of Iowa

Application June 25, 1948, Serial No. 35,188

11 Claims. (Cl. 98—40)

1

This invention relates in general to a grille construction wherein a plurality of louvres are mounted for individual adjustment within a frame, and the primary object of the invention is to provide a new and novel form of mounting means whereby the louvres can be independently rotated for adjustment.

Another object of the invention is to provide a novel form of mounting means for the louvres of a grille whereby each louvre may be individually adjusted and held in its adjusted position by a novel form of frictional holding means.

A further object of the invention is to provide a novel form of mounting means for the louvres of a grille, which mounting means are located intermediate the ends of the louvres and extend therethrough.

Still another and more specific object of the invention is to provide a mounting means for the louvres of a grille wherein a rod will extend through the louvres in a direction transverse thereto, the rod having a plurality of spaced apart spherical or cylindrical elements adapted to cooperate with openings in the louvres for rotatably mounting the louvres for individual adjustment.

A still further object of the invention is the provision of novel frictional means for engaging the ends of the louvres in a grille, whereby each louvre is adjustably mounted and may be held in its adjusted position by the frictional means.

Still another object is to provide a novel method of attaching the individual louvres of a grille to a mounting means therefor located between the ends of each louvre.

Other objects and advantages of the invention will become apparent upon reading the following description taken in conjunction with the accompanying drawings in which:

Fig. 1 is a perspective view of a grille embodying the present invention;

Fig. 2 is an enlarged horizontal sectional view on the line 2—2 of Fig. 1;

Fig. 3 is a vertical sectional view on line 3—3 of Fig. 1;

Fig. 4 is a fragmentary enlarged view of a portion of the mounting means and one of the louvres before attaching of the louvre thereto;

Fig. 5 is a fragmentary sectional view through a louvre after attachment of the louvre to the mounting means;

Fig. 6 is a perspective view of one of the spacer members utilized on the mounting means;

Fig. 7 is an exploded view of a modified form of the invention;

2

Fig. 8 is a fragmentary elevational view showing the parts of Fig. 7 in assembled relation;

Fig. 9 is a fragmentary elevational view of a still further modified form of the mounting means for the louvre;

Fig. 10 is a vertical sectional view on the line 10—10 of Fig. 9;

Fig. 11 is a fragmentary elevational view of another modified form of the mounting means for the louvre; and

Fig. 12 is a vertical sectional view taken along the line 12—12 of Fig. 11.

For purposes of illustration, the various forms of the invention herein have been illustrated as being embodied in an elongated rectangular grille, although it will be evident as the description proceeds that the particular form or shape of the frame within which the louvres are located is not an important consideration. The invention is particularly adapted for use in connection with a grille which may be utilized in the walls of homes and the like where air is to be forced through a conduit to the grille. The louvres of the grille are each individually mounted for rotation and adjustment so that the direction of air passing through the grille can be easily and quickly controlled.

The novel means and method of mounting the louvres within the frame for individual adjustment includes one or more spindles or rods passing through openings in the louvres and extending in a direction at substantially right angles to the louvres. The rod has a plurality of fastening means thereon which, for purposes of illustration, have been variously shown herein as being spaced spheres or balls or spaced cylindrical elements. In one form of the invention, each sphere is received within an opening in one of the louvres, and that portion of the louvre immediately surrounding the sphere is then worked to cause the material to flow around the sphere and partially surround the same, whereby the louvre may be rotatably supported thereon.

In another form of the invention utilizing the spheres, a sleeve is inserted in an opening in the grille and receives the sphere. The ends of the sleeve are then upset around the sphere and are flanged to hold the parts assembled. When cylinders are used instead of spheres, the cylinders may be rotatably mounted in the louvres either by upsetting that portion of the louvre around the cylinder, or by providing the cylinder with end projections which act as pivot pins.

The other features of the present invention

55 which cooperates with the novel mounting means

just described relates to the friction means at each end of the frame which cooperate with the ends of the louvres to frictionally hold the louvres in their adjusted position.

Referring now more particularly to the drawing and especially to Fig. 1, the frame of the grille is generally indicated by the numeral 1, and, in the illustrated form, consists of substantially parallel upper and lower side members 2 and 3 and end members 4 and 5. The frame shown herein is a conventional form and has a forwardly positioned substantially flat surface 6 with a relatively short rearwardly extending flange 7 on the outer edge thereof. The inner edge of the end and side members extends rearwardly to provide a relatively longer flange 8 within which the louvres 9 are mounted. Each louvre is provided at each end thereof with a pivot pin 10 which passes through a suitable opening in the flange 8.

Referring now more particularly to Fig. 3, the novel form of frictional retaining means for the louvres includes an elongated wire member 11 which is adapted to be positioned on opposite sides of adjacent pivot pins 10. Oppositely extending ears 12 and 13 struck outwardly from the upper and lower parts of the end flanges 8 are adapted to receive and hold the ends of the wire 11. The wire 11 is sufficiently flexible so as to be bent and extend on opposite sides of each of the adjacent pivot pins 10, and yet the wire is sufficiently rigid so that it will bear against the pins 10 thereby providing a frictional engagement therewith.

In the illustrated embodiment of the invention, four of the louvres 9 are shown as extending between the end flanges 8, each louvre being provided at each end thereof with a pivot pin 10 extending through the end flanges 8. The wire 11 is held at its upper end by the outwardly struck ear 12 and then passes downwardly first on one side of the upper pivot pin 10 and then on the opposite side of the next lower pivot pin 10. The wire 11 then continues to engage alternate sides of the pin 10, and the lower end thereof is then held in place by the lower outwardly struck ear 13. Thus, when the louvres are rotated about the pins 10 there will be a sufficient friction created between the pins 10 and the wire 11 at each end of the frame to hold each of the louvres in its adjusted position.

Each louvre is also provided with a novel form of mounting means intermediate the ends thereof, which means includes a transversely extending rod 14 provided with a plurality of spaced apart spherical members 15. Each louvre 9 is initially provided with an opening 16 of substantially the same diameter as each of the spheres 15 so that it will be able to receive one of the spheres 15. The manner of mounting and securing the louvres on the intermediate mounting means will be the same for each louvre, and a description as to the manner of fastening one louvre to this means will suffice for all.

Reference is now made to Figs. 4 and 5, wherein Fig. 4 illustrates one of the louvres 9 in a vertical cross-section showing the opening 16 therein. The rod 14 with the sphere 15 thereon is first inserted within the louvre 9 so that the opening 16 will receive the sphere 15. The next step in the process of attachment is to upset the louvre 9 in the immediate vicinity of the sphere 15 so that the material of the louvre 9 will flow upwardly and downwardly for a short distance around the sphere 15. This will result in an annular groove 17 on the top and bottom of the louvre surround-

ing the sphere 15. Fig. 5 shows the result of this operation and it will be quite evident that the louvre 9 of Fig. 5 can be rotated about its longitudinal axis and about the sphere 15 as its rotatable supporting means. This process may be carried out for as many louvres as there is intended to be in the grille, there being one sphere 15 for each louvre 9 on each rod 14. Only one rod 14 has been shown herein, but it will be evident that more than one such mounting means may be used if desired, for example if the grille is an extremely long one and necessitates a greater number of intermediate supports. A plurality of tubular spacer members 18 may be inserted on the rod 14 after each louvre 9 has been attached thereto.

In actual practice the louvres disclosed herein are formed of metal in an extruding process, so that each louvre is a solid piece and hence the upsetting and flowing of the metal around the various spheres 15 has been deemed to be the best way in which the attachment can be made. The invention is equally applicable, however, to a louvre which is formed of a single strip of thin material and folded upon itself to form a hollow louvre. The same manner of attachment to the spheres may be used, except that the opposite sides of each louvre will be clamped around the sphere to provide a rotatable mounting. Also, the invention is not limited to use in connection with a metal louvre, but the construction is also adapted for use with louvres of plastic or other suitable material which may be upset or worked.

The louvres in the illustrated example are all shown as extending in a horizontal direction within the frame, but it will be evident that the direction in which the louvres extend is not important, since they could be vertical or they could be disposed at an angle between vertical and horizontal. Furthermore, if a novel form of design is desired, the rod or rods 14 could be disposed at an angle other than perpendicular to the louvres. In this latter case, the result would be the same except that the louvres might not be able to be rotated through as great an angle as when the rod and louvres are perpendicular to each other.

The friction means at each end of the frame which are designed to frictionally engage the pins at the ends of the louvres cooperate with the mounting means intermediate the ends of the louvres to accomplish the unitary result of a novel form of mounting means to permit a rotatable adjustment of the louvres individually and hold each louvre in its adjusted position.

Referring now more particularly to Figs. 7 and 8, there is shown a modified form of the mounting means for the louvre similar to that illustrated in Figs. 4 and 5 but wherein an additional member is introduced into the assembly for retaining the spherical enlargements within the opening of the louvre for pivotal movement. In these figures, the louvre is indicated by the numeral 19 and is shown as having an opening 20 therethrough. In this form of the invention, the opening 20 is preferably circular in form. A sleeve 21 having an annular flange 22 at one end thereof is adapted to be received within the opening 20 in the louvre and to have a snug fit therein. The inside diameter of the sleeve 21 is such as to be capable of receiving a spherical enlargement 23 on the rod which forms the mounting means. After the sphere 23 is in place, within

the sleeve 21, the sleeve is then upset so as to provide flanges 24 on one end thereof and the flange 22 at the opposite end is bent inwardly toward the louvre whereby the sleeve is held against removal. The sleeve is then further upset so that the area between the ends thereof is formed into an arcuate shape partially surrounding the sphere 23 as shown at 39, thus instead of the louvre itself being upset as shown in Fig. 5, the sleeve 21 is used as a retaining means and has its intermediate portion upset to retain the sphere. The louvre 19 will therefore be capable of a rotary movement around the sphere 23 in the manner heretofore described. It is possible to employ wood louvres in this type of construction.

In Figs. 9 and 10 the enlargement on the rod is shown as being cylindrical rather than spherical. The louvre 25 is provided with a rectangular opening 26 therethrough which is adapted to receive the cylindrical member 27. The area of the louvre immediately surrounding the cylinder 27 is then upset as shown at 28 to provide upper and lower arcuate portions, thereby retaining the cylinder within the opening and preventing its removal therefrom, but permitting the relative rotative movement between the cylinder and the louvre. In this case, the cylinder 27 has an opening therethrough adapted to receive the rod 29 which rod is upset on each side of the cylinder as shown at 30 to thereby retain the cylinder against movement along the length of the rod. Here again the rod 29 is equivalent to the rod 14 shown in Fig. 1 and is used for mounting a plurality of the louvres 25 for individual rotative movement.

Figs. 11 and 12 illustrate a further modification of the retaining means whereby the louvres are mounted for individual rotation. In this form of the invention, the louvre 31 has a rectangular opening 32 therethrough together with smaller openings 33 extending outwardly from each side of the larger opening 32. These openings are adapted to receive a cylindrical member 34 which has at each end thereof the outwardly extending pins 35. The cylindrical member 34 is received within the large opening 32, and the pins 35 are received within the smaller openings 33. The cylindrical member 34 also has an opening 36 therethrough for the reception of the retaining rod 37. As stated before, the metal of the louvre immediately surrounding the cylinder 34 and pins 35 may be upset to form arcuate portions which retain the cylinder and enable a relative rotative movement to be accomplished between the louvre and the cylinder. The rod 37 may also be upset as at 38 on opposite sides of the cylinder 34 to thereby retain the cylinder on the rod.

Each form of the invention, as described above, is adapted to be used in combination with the friction means at each end of the frame whereby the louvres may be frictionally held in any position to which they may be adjusted after they have been rotated about the particular mounting means.

Changes may be made in the form, construction and arrangement of parts from that disclosed herein without in any way departing from the spirit of the invention or sacrificing any of the attendant advantages thereof, provided, however, that such changes fall within the scope of the claims appended hereto.

The invention is hereby claimed as follows:

1. A grille construction, comprising a frame, a plurality of louvre vanes mounted within said

frame, and means intermediate the ends of said vanes for mounting each of the vanes for independent rotation and adjustment with respect to each other, said means comprising a member supported from the frame, an arcuately surfaced enlarged portion associated with said member for each of said vanes and an opening in each of said vanes the sides of which are substantially complementary to and cooperative with said arcuate surface of said enlargement.

10 2. A grille construction, comprising a frame, a plurality of louvre vanes mounted within said frame, means intermediate the ends of said vanes for mounting each of said vanes for independent rotation and adjustment with respect to each other, said means comprising a member supported from the frame, an arcuately surfaced enlarged portion associated with said member for each of said vanes and an opening in each of said vanes, the sides of which are substantially complementary to and cooperative with said arcuate surface of said enlargement, and means to retain each of said vanes in adjusted position.

15 3. A grille construction, comprising a frame, a plurality of louvre vanes mounted within said frame, means intermediate the ends of said vanes for mounting each of said vanes for independent rotation and adjustment with respect to each other, said means comprising a member supported from the frame, an arcuately surfaced enlarged portion associated with said member for each of said vanes and an opening in each of said vanes, the sides of which are substantially complementary to and cooperative with said arcuate surface of said enlargement, and means to frictionally retain each of said vanes in adjusted position.

20 4. A grille construction, comprising a frame, a plurality of louvre vanes mounted within said frame, means intermediate the ends of said vanes for mounting each of said vanes for independent rotation and adjustment with respect to each other, said means comprising a member supported from the frame, an arcuately surfaced enlarged portion associated with said member for each of said vanes and an opening in each of said vanes, the sides of which are substantially complementary to and cooperative with said arcuate surface of said enlargement, and means at each end of said frame operatively associated with said vanes to frictionally retain each of said vanes in adjusted position.

25 5. A grille construction, comprising a frame, a plurality of louvre vanes mounted within said frame, a rod extending between opposed sides of said frame in a direction transverse to said vanes, said vanes being provided with aligned openings, and cooperating means on said rod and said vanes to mount said vanes for independent rotation and adjustment including an arcuately surfaced enlarged portion associated with said rod for each of said vanes and secured in each of said openings.

30 6. A grille construction, comprising a frame, a plurality of louvre vanes mounted within said frame, a rod extending between opposed sides of said frame, cooperating means on said rod and said vanes to mount said vanes for independent rotation and adjustment, said vanes each being provided with an opening having arcuate sides and said cooperating means on said rod comprising an arcuately surfaced enlarged portion complementary to and cooperating with the said sides of said opening, and means at an end of said frame for frictionally retaining each of said vanes in adjusted position.

35 7. A grille construction, comprising a frame,

a plurality of louvre vanes mounted within said frame, a rod extending between opposed sides of said frame and passing through openings in said vanes, a plurality of substantially spherical enlargements on said rod in spaced relation, one of said enlargements being located within the opening of each vane, and each vane being upset in the area surrounding the enlargement therein, thereby to partially surround the enlargement and form a pivotal support for the vane; 10

8. A grille construction comprising a frame, a plurality of louvre vanes mounted within said frame, a rod extending between opposed sides of said frame, and passing through openings in said vanes, a plurality of enlargements on said rod in spaced relation, one of said enlargements being located within the opening of each vane, and means in the opening of each vane partially surrounding the enlargement therein, whereby 20 the vane may be rotated about said enlargement as a center for purposes of adjustment.

9. A grille construction comprising a frame, a plurality of louvre vanes mounted within said frame, a rod extending between opposed sides of said frame, and passing through openings in said vanes, a plurality of substantially spherical enlargements on said rod in spaced relation, one of said enlargements being located within the opening of each vane, a tubular sleeve located 30 within the opening of each vane and surrounding the spherical enlargement therein, and means at opposite ends of said sleeve, cooperating with the vane to retain said sleeve in place, and the portions of said sleeve intermediate the ends 35 thereof being arcuate to thereby partially surround the spherical enlargement therein and form a pivotal support for the vane.

10. A grille construction comprising a frame, a plurality of louvre vanes mounted within said 40

frame, a rod extending between opposed sides of said frame and passing through openings in said vanes, a plurality of cylindrical members mounted on said rod in spaced relation, one of said cylindrical members being located within the opening of each vane, and each vane being upset in the area surrounding the cylindrical member therein, thereby to partially surround the cylindrical member and form a pivotal support for the vane.

11. The combination of elements as defined in claim 10 combined with a pivot pin extending outwardly from each end of said cylindrical member and received within corresponding openings in each of said vanes, the material of the vane immediately surrounding each of said pins, being upset to partially surround the pins, thereby to form a pivotal support for the vane.
